SIX POLE TELEVISION AND RADIO ANTENNA

Sam Gertz, Chicago, Ill.; Sylvia Edith Gertz executrix of
said Sam Gertz, deceased

Application March 14, 1958, Serial No. 50,028

Term of patent 7 years

(Cl. D26—14)

Fig. 1 is a front elevational view of a six pole television and radio antenna showing my new design;

Fig. 2 is a side elevational view thereof; and

Fig. 3 is a top plan view thereof.

The fragmentary broken-line showings of connecting cord in Figs. 2 and 3 are for illustrative purposes only.

The dominant features of the design reside in the portions shown in full lines.

I claim:

The ornamental design for a six pole television and radio antenna, substantially as shown and described.
